WALLBOARD

James T. Kenney, Antioch, Calif.

Application June 15, 1938, Serial No. 213,815

3 Claims. (Cl. 72—16)

This invention relates to improvements in wallboards and, more particularly, to composite plaster boards and the method of applying such boards to the walls of buildings.

5 Among the objects of the invention is to enable the production of a continuous wall surface, unmarred by visible seams, nail heads, cracks, and other unsightly defects.

Another object is to safeguard the wallboard 10 surface against the formation of cracks at the joints thereof due to bulging or warpage of the wallboard, the stresses incidental to the aging and settling of the building, and to weather conditions.

15 Another object is to obviate the necessity for driving nails through the friable plaster compound which constitutes the body of the wallboard.

Another object is to obviate the necessity for 20 trimming the edges of wallboards during manufacture with the incidental waste of labor and material.

Another object is to provide substantial homogeneity in the material immediately underlying 25 the facing paper of the wallboard in order to minimize superficial surface streaks and irregular discolorations due to differences in the moisture adsorptivities, expansion coefficients, etc., of the underlying layer.

30 Another object is to provide a wallboard which is capable of being satisfactorily installed by home owners themselves, and other unskilled labor.

Another object is to provide a wallboard having 35 the hereinbefore mentioned advantages at substantially the cost of the ordinary plaster board in use heretofore.

Other objects and advantages will appear as 40 this specification progresses.

In this specification and the accompanying 45 drawings, the invention is described in its preferred form. It is to be understood, however, that it may be embodied in other forms within the purview of the claims following the description.

45. In the two sheets of drawings:

Fig. 1 is a perspective view of the upper portion of a joint between two composite plaster boards constructed in accordance with this invention at the completion of the operation of 50 the nailing of the plaster boards to the studding of the building, the adjoining margins of the facing paper being curled back to expose the underlying material strips of the composite boards for nailing.

55 Fig. 2 is a similar fragmentary view of the

same with the margins of the facing paper lapped over each other preparatory to the severing thereof.

Fig. 3 is a similar view of the same subsequent to the severing and gluing operations. 5

Fig. 4 is a horizontal section in somewhat reduced scale of the wallboard construction illustrating the nailing strips intermediate the margins of the wallboard.

Fig. 5 is an enlarged fragmentary horizontal 10 section showing a modified form of intermediate nailing strip structure.

Figs. 6 and 7 are front elevations of modified forms of marginal nailing strips.

In detail, the construction illustrated in the 15 drawings comprises the sheet 1, of "building paper" or similar strong, thin material. The marginal nailing strips 2, 3 and the intermediate nailing strips 4 are preferably composed of laminated wood or the like. Because of the narrow width of the nailing strip and the fact that they are completely concealed in the ultimate product, they can be formed from the trimmings and other rejects of the laminated wood industry. 20

Either organic or mineral glue, as desired, is 25 applied to both sides of the intermediate strips 4 and to one side of the marginal strips 2, 3. The opposite side of the marginal strips 2, 3 has the glued area, as at 5. The remainder of the surface of the strips 2, 3 adjoining the area 5 is left 30 unglued for reasons to be later discussed.

The strips 2, 3 and 4 are laid longitudinally with their completely glued sides down on the sheet 1. They are spaced apart a distance to coincide with the spacing of the studding in 35 the conventional building, which is usually 16 inches. A suitable plaster compound, such as is conventional in the art of plaster wallboard, is poured on to the sheet 1 into the spacing between the strips 2, 3 and 4, as at 6. A sheet 7 of paper 40 is then laid over the central nailing strip and the intermediate wet plaster. The edges 8 and 9 of the sheet 7 extend slightly beyond the marginal strips 2, 3. The sheet 7 may be of paper similar to the sheet 1, or it may be suitably finished in any desired manner, as by stippling, to 45 serve as the final wall surface.

Pressure is applied to the now assembled wallboard by passing it between suitable rolls, or by compressing it in a suitable press. The moisture 50 exudes from the plaster between the sheets 1 and 7 and the glued surfaces of the strips 2, 3, and 4, thus cementing these strips to the enclosing sheets. Should the plaster compound contain a sufficient quantity of a mineral cement such as 55

water glass (sodium silicate), the preliminary gluing of the strips 2-4 may be omitted, since the waterglass will then serve to cement the strips to the opposing sheets.

- 5 If desired, the intermediate nailing strip 4 may be thinner than the marginal strips 2, 3, as at 4x in Fig. 5. The plaster will then flow over the strips 4x as at 4xx, interposing a layer of plaster between the strips 4x and the sheet 1. This provides a layer of homogeneous material behind the facing sheet 7 for practically the whole width of the wallboard, thus providing substantially uniformity of coloration of the sheet 6 throughout the life of the wallboard.
- 10 15 Subsequent to the pressing of the wallboard, it is dried and otherwise processed in accordance with the well known technique in this art.

The marginal strips 2, 3 preferably have the dove tail edges 10, 11, as in Fig. 1, although curvilinear or straight edges 10x, 11x, or 10xx, 11xx, as in Figs. 6 and 7 respectively, may be substituted.

20 The marginal strips 2, 3 provided by the present invention serve as the finished edges of the wallboard, thus eliminating the necessity for trimming the edges of the wallboard during manufacture with the incidental wastage of labor and materials.

25 In installing the wallboard, the edges 1, and 8 of the facing sheet 7 are curled back, as in Fig. 1, to expose the strips 2, 3 for nailing. This is rendered possible by leaving the surface of the strips 2, 3 adjacent the area 5 unglued in the fabrication of the wallboard, as above described.

30 35 The composite board is nailed to the frame of the building by means of the finishing nails 12, which are driven through the nailing strips 2, 3 into the studding x. Since the nails are not driven through the friable plaster slab 6, large flat head

40 45 nails are not required, and the number of nails necessary is relatively small.

Small finishing nails are also driven through the intermediate nailing strips 4 which register with the studs y, z of the building frame. The heads of these nails are easily concealed by putty or similar material. The adjoining wallboards have their dove-tail edges 10, 11 interlocked with the dove-tail edges 10, 11 of the marginal nailing strips 2, 3 of the wallboard already installed.

50 They are then similarly nailed to the studding.

When the wallboards are in place, the curled-back margins 8, 9 of the facing sheet are overlapped as in Fig. 2. The overlapped portions are then severed by a single incision of a knife or other sharp instrument, as at A. The cut-away material is then removed, as in Fig. 3, bringing the severed edges 8, 9, 9' into abutment. It is not necessary that the severing at A be accomplished along a straight line, since the edges 8', 9' will nevertheless be in abutment provided the 10 incision at A is clean.

After the severing operation, the margins are glued over the strips 2, 3, concealing the nails 12 and leaving only an almost invisible seam.

Having thus described this invention, what I claim and desire to secure by Letters Patent is:

1. A wallboard comprising a slab of friable material; marginal nailing strips of substantially the same thickness as said slab of material having nailing characteristics superior to those of said slab and fixed to opposite edges of said slab in substantially the plane thereof, a backing sheet of fibrous material directly adhering to the rear surface of said slab and strips; and a facing sheet of thin material directly adhering to the front surface of said slab and strips, the edges of said facing sheet being adapted to overlap the edges of the facing sheet of an adjoining wallboard.

2. A wallboard comprising a slab of friable material between two sheets of fibrous material; and marginal nailing strips of material having nailing characteristics superior to those of said slab and fixed to the opposite edges of said slab in substantially the plane thereof, the edges of said nailing strips being arranged to interlock with the edges of the nailing strips of adjoining wallboards.

3. A wallboard comprising a slab of friable material; marginal wooden nailing strips fixed to the opposite edges of said slab in substantially the plane thereof, the edges of said nailing strips being arranged to interlock with the edges of the nailing strips of adjoining wallboards; a backing sheet of fibrous material adhering to the rear surface of said slab and strips; and a facing sheet of flexible material adhering to the front surface of said slab and strips, the edges of said facing sheet being adapted to overlap the edges of the facing sheet of an adjoining wallboard.

JAMES T. KENNEY. 50
